UNITED STATES PATENT OFFICE.

CHARLES ALBERT FISHER, OF THOROLD, CANADA, ASSIGNOR OF ONE-TENTH
TO CURT C. ANDREWS, OF NORTH TONAWANDA, NEW YORK.

FRICITION-CLUTCH.

SPECIFICATION forming part of Letters Patent No. 706,400, dated August 5, 1902.

Application filed October 15, 1901. Serial No. 78,720. (No model.)

To all whom it may concern:

Be it known that I, CHARLES ALBERT FISHER, a citizen of the United States, residing at Thorold, in the Province of Ontario, Canada, have invented certain new and useful Improvements in Friction-Clutches; and I do hereby declare the following to be a full, clear, and exact description of the invention, such as will enable others skilled in the art to 10 which it appertains to make and use the same.

My invention relates to friction-clutches; and its primary object is to provide a simple, inexpensive, and effective device of the character named in which the operative mechanism will be entirely inclosed, thus avoiding projecting parts and presenting only smooth surfaces on the exterior of the clutch. I thus avoid the danger of injury to workmen caused by the contact of their hands or clothing with projecting revolving parts of the clutch.

The invention comprises a pulley loosely mounted upon a shaft, a disk fixed upon the shaft, friction devices carried by said disk, 25 and a sleeve slidably supported upon the shaft for operating the friction devices.

The construction of the improvement will be fully described hereinafter in connection with the accompanying drawings, which form 30 part of this specification, and its novel features will be defined in the appended claims.

In the drawings, Figure 1 is an elevation of the clutch in its closed position. Fig. 2 is a similar view showing the clutch in its open or 35 released position. Fig. 3 is a section taken on the line 3 3 of Fig. 4. Fig. 4 is a transverse section showing the inner side of the disk and the friction devices secured thereto in elevation; and Fig. 5 is a detail section, on an enlarged scale, of one of the pivotal supports of 40 the friction devices.

The reference-numeral 1 designates a shaft, upon which is loosely mounted a pulley comprising a sleeve 2, a disk 3, and an annular 45 horizontal flange 4. The pulley is supported in position upon the shaft by a ring 5 and a set-screw 6.

7 designates a disk formed with an integral sleeve portion 8, which is fixed to the shaft 50 by means of a suitable key 9. The sleeve 8 of the disk is formed at diametrically opposite points with elongated slots 10, within each

of which is pivotally secured an arm 11. The inner ends 12 of these arms extend within the pulley, as shown in Fig. 3, and are hooked to 55 engage the links 13, by means of which the arms are connected to the hooked ends 14 of curved levers 15.

The levers 15 are pivotally secured to the inner side of the disk 7 at the points 16 and 60 at their outer ends to friction-shoes 17, said shoes being rounded to conform to the inner surface of the flange 4 of the pulley. The shoes 17 are oppositely disposed, as shown in Fig. 4, and are pivotally secured adjacent to 65 their ends to links 18, the inner ends of which are pivotally secured to bosses 19, projecting from the inner side of the disk 7 and adjustably secured thereto by bolts 20 and nuts 21. The bolts 20 are adjustably secured by set- 70 screws 22.

The levers 15 are secured to the disk by coil-springs 23.

24 designates a sleeve slidably mounted upon the shaft and adapted to be forced over the 75 arms 11 to press said arms toward each other and force the friction-shoes into engagement with the inner surface of the flange 4 of the pulley. The sleeve 24 is provided with an integral grooved extension 25 to receive a 80 shifting ring 26, adapted to be operated by a lever 27, as illustrated in Fig. 1.

The operation of the mechanism as thus described is as follows: When the sleeve 24 is in the position shown in Fig. 2, the friction-shoes will be out of contact with the flange of the pulley, and said pulley will be thus released and will not turn with the shaft; but when the sleeve 24 is moved inward to the position shown in Figs. 1 and 3 the arms 90 11 will be moved toward each other, thus tilting the curved levers 15 and forcing the shoes into frictional engagement with the inner surface of the pulley-flange 4. The pulley and disk are thus firmly locked together to turn 95 with the shaft. When the sleeve 24 is moved outward to the position shown in Fig. 2, the springs 23 retract the curved levers to release the friction-shoes. By means of the bolts 20 and the set-screws 22 the friction-shoes may 100 be adjusted to compensate for wear.

It will be noted that by the construction above described all of the operative mechanism is inclosed within the pulley and smooth

surfaces are presented on both sides of the device as well as on the periphery of the pulley, and hence the liability of injury to workmen or others is entirely avoided.

5 I would have it understood that the invention is not restricted to all of the details of construction shown and described, but that I reserve the right to make all such modifications and changes as may properly fall 10 within the scope of the invention as set forth in the following claims.

I claim—

1. A friction-clutch comprising a revolvable pulley, a fixed disk, arms pivotally secured to the disk, levers fulcrumed upon the disk and having friction-shoes, connections between the arms and levers, and laterally-movable means for operating the arms and levers.
2. A friction-clutch comprising a loosely-mounted pulley, a fixed disk having a slotted sleeve extension, arms pivotally secured with-

in said extension, oppositely-disposed levers fulcrumed upon said disk, connections between said arms and levers, a sliding sleeve 25 for operating said arms and friction-shoes secured to said levers.

3. A friction-clutch comprising a loosely-mounted pulley; a fixed disk having a sleeve extension; arms pivotally secured within the 30 said extension; oppositely-disposed curved levers fulcrumed upon said disk and connected to the ends of said arms; retracting-springs for said levers; friction-shoes adjustably supported upon the inner face of said disk; and a sliding sleeve for forcing said arms toward each other.

In testimony whereof I affix my signature in presence of two witnesses.

CHARLES ALBERT FISHER.
